UNITED STATES PATENT OFFICE.

CHARLES F. STAPLES, OF DETROIT, MICHIGAN.

WASHING MACHINE.

Application filed May 26, 1921. Serial No. 472,658.

To all whom it may concern:

Be it known that I, CHARLES F. STAPLES, a citizen of the United States, residing at Detroit, county of Wayne, State of Michigan, have invented a certain new and useful Improvement in Washing Machines, and declare the following to be a full, clear, and exact description of the same, such as will enable others skilled in the art to which it pertains to make and use the same, reference being had to the accompanying drawings, which form a part of this specification.

My invention relates to washing machines. The object is to provide a unitary washer and dryer of simple, inexpensive construction adapted for ease in operation and capable of thoroughly washing and drying clothes in a minimum of time. A further object is to provide a washer and dryer adapted to be driven from the same source of power supply, by the same shaft at a minimum of power expenditure.

A further object is to provide a unitary, self contained, washer and dryer in which the centrifugal drying basket is superimposed over the washing vat and driven by the driving shaft extending through the bottom of said vat.

A further object is to provide a washing machine in which the centrifugal drying basket is superimposed over the washing vat and mounted within the same casing for rotation, and adapted to be driven concurrently with the driving of washing element positioned in the vat from the same source of power supply.

These and other objects together with details of construction will more fully appear from the following description, appended claims and accompanying drawings, in which:

Figure 1 is a vertical section through my washing machine.

Fig. 2 is a plan view.

Fig. 3 is a horizontal section taken on the line 3—3 of Fig. 1.

In the drawings let *a* indicate a casing, the lower portion of which is adapted to serve as a washing vat indicated as *a*², which casing is suitably supported from the floor by means of three legs *b*, which carry a base plate *c*, upon which the casing rests. A drain plug *d* is provided for the vat. The vat is provided with obstructions or radial wings *a*³ extending inwardly from the wall thereof, which may be supplied in such

number as may be desired, either being fastened separately in place or the wall corrugated to form such obstructions.

Supported below the base plate is a motor *e* which may be slidably mounted as shown so as to be moved radially the vat by means of a screw *e*² so as to adjust the driving relationship between the bevel driving gear *f* and the driven gear *f*² which is carried by the driving spindle *g*. This driving spindle extends axially through the bottom of the vat and is journalled in the housing *h* by means of bearings *h*² and *h*³. This spindle carries a smooth, conical, washing element *i*, which extends downwardly almost to the bottom of the vat, the lower edge of this element being bent outwardly to form a radial flange and which washing element rotates with the spindle.

Adapted to be received within the upper portion of the casing *a*, superimposing the vat, is a centrifugal drying basket *k*, the wall and bottom of which is perforated as at *k*², such perforations being provided in any desired number. This basket is provided with an axially positioned hollow handle *m* which is adapted to receive the driving spindle *g*. A friction plate *n* is provided adapted to intervene the bottom of the basket and the upper bearing surface formed on the end of the washing element *i* so that the drying basket will rotate with the spindle concurrently with the rotation of the washing element. By means of the handle the dryer may be removed allowing the washing element to rotate alone. The bottom of the centrifugal drying basket carries an annular washing member *k*³ which extends downwardly within the vat and is adapted to frictionally engage the water to set up a rotary movement thereof in the vat.

The casing is provided with a cover *s*. A drainage pipe *o* leads from the side of the casing and is adapted to drain away the water discharging from the dryer, which water is prevented from falling into the washing vat by means of an annular flange *p* which slopes upwardly from the casing partially overhanging the vat and which flange collects the water thrown from the dryer.

The bottom of the dryer is provided with a door *q* which may be removed to permit the clothes to be taken from the vat and placed in the dryer without removing the dryer from the driving shaft. This door is here shown as secured in place by means of

eccentric locking pins *r*. Such catches however are unnecessary as the door would remain in position during the operation of the machine.

5 In the operation of this machine the centrifugal dryer and washing element rotate concurrently at a suitable speed, such as 200 R. P. M., therefore, the drying operation goes on at the same time as the washing 10 operation. The swirling rotary motion of the water set up in the vat by means of the rotation of the washing element forces the water through the clothes, thereby cleansing them. On the completion of the washing of 15 one batch of clothes they are removed through the door in the dryer and placed in the dryer where they may be dried at the same time that the washing of the second batch of clothes is taking place in the washing 20 vat. The clothes may be successfully rinsed in the dryer in the same manner concurrently with the washing operation.

What I claim is:

1. In a washing machine, a vat, a drive 25 shaft extending upwardly through the bottom thereof, a washing element carried by the shaft disposed in the lower portion of the

vat, a perforated drying basket disposed in the upper portion of the vat and engaging with the drive shaft above the washing element to be rotated with the shaft, and a 30 drainage collector associated with the vat intermediate the drying basket and washing element to catch the discharge from the basket and prevent it from falling into that 35 portion of the vat occupied by the washing element.

2. In a washing machine, a vat, a drive shaft extending upwardly through the bottom thereof, a perforated rotatable drying basket carried by said shaft for rotation in the upper portion of the vat, and an annular 40 washing element depending from the basket into the lower portion of the vat.

3. In a washing machine, a vat, in the lower portion of which a movable washing element is disposed, and a perforated drying basket positioned within the upper portion of the vat superimposed above the portion in 45 which the washing operation occurs.

In testimony whereof I sign this specification.

CHARLES F. STAPLES.
